COVER FOR CONDIMENT CONTAINERS
OR THE LIKE

James Baldwin Swett, Barrington, R.I., assignor to Rexall Drug and Chemical Company, Los Angeles, Calif., a corporation of Delaware

Filed July 3, 1968, Ser. No. 12,623

Term of patent 14 years

Int. Cl. D9—02

U.S. Cl. D9—275

FIG. 1

FIG. 2

FIG. 3

FIG. 4

FIG. 5

FIG. 6

FIG. 7

FIG. 8

FIG. 1 is a perspective view of a cover for condiment containers or the like embodying my new design;

FIG. 2 is another perspective view with the top lid in an opened position;

FIG. 3 is a top plan view;

FIG. 4 is a side view;

FIG. 5 is a front view;

FIG. 6 is a back view;

FIG. 7 is a bottom view; and,

FIG. 8 is a cross-section taken on line 8—8 of FIGURE 3.

I claim:

The ornamental design for a cover for condiment containers or the like, substantially as shown.
